DESIGN FOR A HAIR ORNAMENT

Rebecca Tawdish, New York, N. Y., assignor to Ben Hur Products, Inc., a corporation of New York

Application November 27, 1942, Serial No. 108,890

Term of patent 3½ years

To all whom it may concern:

Be it known that I, Rebecca Tawdish, a citizen of the United States, residing at New York city, in the county of Bronx and State of New York, have invented a new, original, and ornamental Design for a Hair Ornament, of which the following is a specification, reference being had to the accompanying drawing forming a part thereof, in which:

Fig. 1 is a front elevational view of a hair ornament, showing my new design.

Fig. 2 is a top plan view thereof; and
Fig. 3 is an end elevational view thereof.

I claim:

The ornamental design for a hair ornament,
substantially as shown.
